Primary Examiner — Terry Wallace(74) *Attorney, Agent, or Firm* — McDermott Will & Emery LLP(57) **CLAIM**

The ornamental design for a burger press, as shown and described.

DESCRIPTION

FIG. 1 is an exploded view of the burger press showing my new design, in a first position.

FIG. 2 is an exploded view thereof in a second position.

FIG. 3 is an exploded view thereof in a third position.

FIG. 4 is an exploded view thereof in a fourth position.

FIG. 5 is an exploded view thereof in a fifth position.

FIG. 6 is an exploded view thereof in a sixth position.

FIG. 7 is a perspective view thereof in an assembled position.

FIG. 8 is a top plan view of FIG. 7.

FIG. 9 is a cross-section taken along line 9-9 of FIG. 8.

FIG. 10 is a cross-section taken along line 10-10 of FIG. 9.

FIG. 11 is a cross-section taken along line 11-11 of FIG. 9.

FIG. 12 is an exploded view thereof in a seventh position.

FIG. 13 is a cross-section taken along line 13-13 of FIG. 12; and,

FIG. 14 is a cross-section taken along line 14-14 of FIG. 12. The broken lines are for illustrative purposes only and form no part of the claimed design.

1 Claim, 14 Drawing Sheets---
